UNITED STATES PATENT OFFICE

109,717

DESIGN FOR A BRACKET THERMOMETER OR THE LIKE

Morris Kominz, Rochester, N. Y.

Application March 23, 1938, Serial No. 76,036

Term of patent 7 years

To all whom it may concern:

Be it known that I, Morris Kominz, a citizen of the United States, residing at Rochester, in the county of Monroe and State of New York, have invented a new, original, and ornamental Design for a Bracket Thermometer or the Like, of which the following is a specification, reference being had to the accompanying drawing, forming part thereof.

In the drawing:

Fig. 1 is a face view of a bracket thermometer showing my new design;

Fig. 2 is a top plan view thereof, and

Fig. 3 is an end view thereof.

I claim:

The ornamental design for a bracket thermometer or the like, as shown.

MORRIS KOMINZ.
